UNITED STATES PATENT OFFICE

GEORGE H. EMERSON AND WILLIAM B. WHITSITT, OF BALTIMORE, MARYLAND

LOCOMOTIVE BOILER

Application filed June 8, 1928. Serial No. 283,813.

This invention relates to locomotive boilers of the water-tube fire-box type, and particularly to boilers of this character designed to supply superheated steam in large

5 volume and at a high working pressure.

With locomotive boilers of this type of conventional construction it is impossible to produce a barrel capable of safely carrying a steam pressure as high as 500 lbs. per

10 square inch because of the impracticability of employing metal of essential thickness to give the necessary four factors as required by the Interstate Commerce Commission for locomotive boilers in interstate service.

15 For example, if a barrel of 80" is used in order to enable it to carry a pressure of 500

lbs. per square inch, metal of a thickness of 1 $\frac{1}{8}$ " is required. Metal of this thickness is not only very difficult to roll or bend to

20 form, but cannot be practically used because of its tendency to quickly crack longitudinally under the imposed strains. The making of a longitudinal joint with metal of this dimension which will be steam tight

25 at such high pressure is also practically impossible because of the difficulty of driving rivets through a plurality of layers of material of this thickness.

One object of our invention is to provide

30 a divided type of barrel generator comprising a group of drums serving as the water containing and steam generating means, by means of which a generator is produced which is capable of rapidly and efficiently

35 generating and safely carrying a steam pressure of 500 lbs. per square inch or over, while at the same time admitting of the use of readily worked thin metal giving the necessary safety factors and keeping the weight

40 of this part of the locomotive desirably low.

Another object of our invention is to provide a novel construction of water-tube fire-box generator whereby a generator of maximum strength is produced and whereby a

45 more efficient circulation of water and steam is obtained and the available heat utilized to greater advantage for rapid steam generation.

With these and other objects in view, the

struction, combination and arrangement of parts, hereinafter fully described and claimed, reference being had to the accompanying drawings, in which:—

Figures 1 and 2 are, respectively, a sectional side elevation of the fire-box portion and a part of the barrel portion, and a side elevation of the remainder of the barrel portion and the smoke-box portion, of a locomotive embodying our invention, unessential parts being omitted, the line $x-x$ indicating the plane of division between the two days.

Figure 3 is a view from the rear, looking forwardly, of the fire-box portion of the boiler as viewed on one side of its vertical center.

Figure 4 is a vertical transverse section, looking forwardly, through the rear part of the fire-box portion of the boiler on the opposite side of its vertical center.

Figure 5 is a vertical transverse section on opposite sides of the vertical center of the barrel portion of the boiler and of the smoke-box portion thereof, the latter taken on the plane indicated by line 5—5 of Figure 2.

Figure 6 is a similar view through the barrel portion of the boiler on the opposite side of its transverse center taken on the plane indicated by line 6—6 of Figure 2.

Figure 7 is a vertical transverse section through one side of the smoke-box portion of the boiler taken on the plane indicated by line 7—7 of Figure 2.

Figure 8 is a top plan view of the hollow fire-box frame.

Figure 9 is a side elevation thereof.

Referring now more particularly to the drawings, A, B and C, respectively, designate the fire-box, barrel and smoke-box portions of the locomotive, said portions being enclosed by outer shells A', B' and C' of suitable construction. The fire-box portion A includes the rear portions of a pair of longitudinally extending upper drums 1 and 2, upper headers 3 and 4 arranged parallel with and on the outer sides of said drums and between the same and the shell A', and a hollow bottom frame member 5 of the outline form of a rectangular ring or loop, the

portions of which provide front and rear lower headers 6 and 7 and side headers 8 and 9. The headers 3 and 4 and the frame member 5 are preferably castings of rectangular cross-section, but they may be otherwise made and of other cross-sectional form. As shown, the drums 1 and 2 are connected with the headers 6 and 7 at spaced intervals by nipples 10, for the flow of water and steam from each header to the adjacent drum, and the side headers 8 and 9 of the frame member 5 are connected with the headers 3 and 4 by sets of water tubes 11 and 12, while the headers 6 and 7 are connected with the drums 1 and 2 by sets of water tubes 13 and 14. Each set of water tubes 11 and 12 comprises two or more rows of staggered tubes arranged closely together, while each set of tubes 13 and 14 consists of two groups of tubes equal in number to each other and connecting the headers 6 and 7 on opposite sides of the longitudinal center of the boiler with the respective drums 1 and 2. The tubes 11, 12 and 14 are more or less straight and extend more or less directly between the parts which they connect, the tubes 14 leading vertically from the header 7 to the rear ends of the drums 1 and 2, so that such tubes 11, 12 and 14 provide more or less direct paths for the free and unrestricted flow of water from the bottom header to the top headers and drums. The tubes 13 on the other hand extend from the header 6 at an upward and rearward angle of inclination and connect at their rear ends with the drums 1 and 2 between the rear end of the fire-box and its transverse center. These tubes 13 thus arch over the grate, which may be enclosed and supported by the frame member 5, so that such tubes will be intensively heated by the combustion gases and, by connecting the front header 6 with the rear portions of the elevated drums, will serve to equalize the water and steam circulation between the lowest and highest portions of the circulating system. All the tubes are rolled at their ends into receiving openings in the headers and drums and the headers are provided in their walls opposite those in which the holes are formed with openings normally closed by removable plugs 15, these openings permitting convenient rolling in of the tube ends, and convenient cleaning of the tubes by turbining or otherwise whenever required. The drums 1 and 2 extend the full length of the fire-box and barrel with their rear ends projecting through the back head 16 of the fire-box and their front ends projecting through the partition sheet 17 between the barrel and smoke-box. Each end of each drum is provided with a head 18 having a manhole closed normally by a manhole plate or cover 19, on the removal of which heads access to

the drums is permitted for cleaning, repairs and other purposes.

Arranged within the barrel and cooperating with the drums 1 and 2 to form the water containing and steam generating means within the barrel are drums 20, 21, 22, 23 and 24, the drums 20, 21 and 22 being disposed intermediately of the depth of the barrel and in transverse alignment and the drums 23 and 24 being disposed at the bottom of the barrel in vertical alignment with the drums 1 and 2. The water containing and steam generating space of the barrel is thus composed of or divided up into seven drums, but the invention is not necessarily limited to this particular number of drums. As shown, the top and bottom drums and outer drum of the set of drums at each side of the vertical center of the barrel are connected by nipples 25, and the top and bottom drums at each side of the vertical center of the barrel are also connected with the central drum of the intermediate set of drums by nipples 26, thus providing for an equalized flow of water and steam between all the drums. The front ends of the upper drums 1 and 2 are connected by branch pipes 27 to a dry pipe 28, through which the steam generated by the fire-box and barrel generators is delivered to the saturated steam chamber of the superheater header 29 arranged within the smoke-box, while the rear ends of the bottom drums 23 and 24 are connected by branch pipes 29 to a pipe 30 connected to the header 6 of the frame member 5 for the supply of water from said drums to the fire-box steam generator.

The forward ends of the drums 20, 21, 22, 23 and 24 are supported by and open through the partition sheet 17 into the smoke-box, while the rear ends of said drums align vertically with the header 6 of the frame member 5. The ends of these drums are closed by flat heads or flue sheets 31. Through all of said drums extend fire tubes 32 and through the drums 20, 21 and 22 extend superheater flues 33, which tubes and flues are suitably fitted in the heads 31. The flues 33 receive the usual superheater units, the ends of which connect with the saturated and superheated steam chambers of the superheater header 29.

The header 6 forms a base support for a wall of firebrick 34 receiving and supporting the rear ends of the drums 21, 22, 23 and 24 and through which the drums 1 and 2 pass, said wall constituting the front wall of the fire-box and the partition wall between the same and the rear ends of the barrel. The side walls of the fire-box are formed by the tubes 11 and 12 and a filling of firebrick 35 closing the spaces therebetween and interposed between said tubes and the sides of the outer shell A', such fire-

brick filling resting on and being supported by the side headers 8 and 9 of the frame member 5. The top of the fire-box is formed by the drums 1 and 2, the headers 3 and 4 and a filling of firebrick 36 closing the spaces therebetween and resting thereon and supported additionally, if desired, by suitable stays between the drums and headers and between said drums and headers and the outer shell A. A firebrick lining for the backhead 16, forming therewith a protected back wall for the fire-box, may also be provided, which lining may rest upon the header 7 of the frame member 5 as a base support. As a result of this construction it will be seen that all the component parts of the fire-box will be securely supported, tied and braced and a steam generator structure therein provided the elements of which are exposed at all sides to the heat of the bed of fuel and the combustion gases, and in which the flow of water and steam to the parts of the generator is effectually equalized, so that economical and rapid steam generation is ensured. By the provision of the hollow frame member 5 the internal strength of the fire-box is not only greatly increased, but, as this frame member serves as a water conductor supplying all the water tubes and the drums 1 and 2 with the feed water from the drums 23 and 24, an even and regular supply of water to all the parts of the fire-box generator is made certain and its flow, and consequently the flow of the steam, is provided for without flow restrictions. As shown, the headers 3 and 4 connect with the drums 1 and 2 at such an elevation that, even when the water level of the boiler falls below the bottoms of these drums, the constant inflow of water from the headers into the drums will keep the bottom portions of the drums covered with water, effectually preventing overheating of the drums and the liability of explosion of these parts. A water tube fire-box generator is thus produced which is of maximum strength and enables a more efficient and reliable circulation of water and steam to be obtained and all the available heat utilized to greater advantage for rapid steam generation.

An important feature of our invention, as stated, resides in the divided or sectional construction of the barrel generator, in which the water containing and steam generating means comprises a series of communicating compartments, preferably in the form of cylindrical drums, as shown, whereby the amount of water required to be carried therein for steam generation may be reduced and the sum total of water divided up into quantities more readily acted upon by the heat for rapid steam generation. At the same time by so constructing the generator of a plurality of drums, properly stayed and braced, metal of the usual $5\frac{1}{8}$ "

thickness may be used and a generator barrel for any size of locomotive conveniently produced for the safe generation and carriage of steam at a pressure of 500 lbs. per square inch or over, which will meet all regulations and requirements without making the barrel of undue or prohibitive weight.

Having thus described our invention, we claim:

1. In a locomotive fire-box steam generator, a pair of drums arranged at the top and on opposite sides of the longitudinal center of the fire-box, communicating front, rear and side headers at the bottom of the fire-box, upper headers arranged on the outer sides of the drums and in communication therewith, a barrel into which the aforesaid drums extend, other drums arranged within the barrel and having their rear ends overhanging the front header at the bottom of the fire-box, water tubes at opposite sides of the fire-box and connecting the upper and lower headers, water tubes connecting the rear lower header with the rear ends of the first named drums, water tubes connecting the front lower header with the first-named drums adjacent to the rear ends of the latter and in advance of the second-named water tubes, fire tubes in the second-named drums, and brickwork resting on the front header at the bottom of the fire-box and enclosing the overlying portions of the drums and forming therewith the front wall of the fire-box.

2. In a fire-box steam generator, drums arranged at the top and on opposite sides of the longitudinal center of the fire-box, communicating front, rear, and side headers at the bottom of the fire-box, upper headers arranged on the outer sides of the drums and in communication therewith, a barrel, other drums arranged in the barrel and having their rear ends overlying the front header at the bottom of the fire-box, sets of water tubes at the sides of the fire-box and connecting the upper headers and bottom side headers, and sets of tubes leading from the front and rear bottom headers and connecting the same with the first-named drums, fire tubes in the second-named drums, and brickwork resting on the front header at the bottom of the fire-box and enclosing the drums and forming with the drums the front wall of the fire-box.

3. In a locomotive fire-box generator, a hollow bottom frame member providing front, rear and side water legs, a pair of drums at the top of the fire-box, upper headers located on the outer sides of said drums, water tubes connecting the side headers of the frame element with the upper header, water tubes connecting the front and rear headers of the frame element with the drums, a barrel into which the aforesaid

- drums extend, other drums arranged within the barrel and having their rear ends overhanging the front water leg of the frame element, fire tubes in the latter-named drums, and brickwork resting on the front and side 5 water legs of the frame element and forming with the drums and side rows of water tubes the front and side walls of the fire-box.
4. In a locomotive fire-box generator, a hollow bottom frame member providing front, rear and side water legs, a pair of drums at the top of the fire-box, upper headers located on the outer sides of said drums, water tubes located on the outer 10 sides of said drums, water tubes connecting the side headers of the frame element with the upper header, water tubes connecting the front and rear headers of the frame element with the drums, a barrel into which the 15 aforesaid drums extend, other drums arranged within the barrel and having their rear ends overhanging the front water leg of the frame element, fire tubes in the latter-named drums, brickwork resting on the side 20 water legs and front water leg of the frame element and forming with the drums and side water tubes the front and side walls of the fire-box, and brickwork at the top of the fire-box and forming with the upper 25 drums and upper headers the top wall of the fire-box.
5. In a locomotive, a fire-box, a barrel, said fire-box having a water tube steam generator comprising front, rear and side bottom headers, a grate enclosed thereby, a pair of upper drums extending longitudinally of the fire-box and barrel, upper water headers connected with said drums, water tubes connecting the lower headers with the 30 upper headers, and front and rear sets of water tubes, the former arching over the grate, connecting the front and rear headers with the rear ends of the drums at spaced intervals transversely of the fire-box, and the 35 barrel having a steam generator comprising the forward portions of the aforesaid drums and a plurality of underlying drums, the lowest drums in the barrel being in water communication with the front header of the 40 fire-box generator.
6. A locomotive having a fire-box, a barrel, upper drums extending longitudinally of the fire-box and barrel, means within the fire-box and including a water container 45 having a horizontal transverse water leg co-acting with the portions of the upper drums therein to form a water-tube fire-box steam generator, lower and intermediate drums within the barrel and having their rear ends overhanging said water leg, said drums forming with the portions of the upper drums therein a steam generator, fire tubes in the drums in the barrel a water flow connection between the lower drums of the barrel 50 generator and the bottom of the fire-box.
- generator, firebrick resting on said water leg and enclosing the drums and forming therewith the front wall of the fire-box, and steam delivery means leading from the upper drums.
7. A locomotive having a fire-box, a barrel, upper drums extending longitudinally of both the fire-box and the barrel, a frame element at the base of the fire-box forming front, rear and side headers, upper headers 70 within the fire-box alongside said drums, rows of tubes at the sides of the fire-box connecting the side headers of the frame element with the upper headers, rows of water tubes connecting the front and rear 75 headers of the frame element with the drums, lower and intermediate drums within the barrel and having their rear ends overhanging the front header of the frame element, a water flow connection between 80 the lower drums in the barrel and the front header of the frame element, a brickwork resting on the frame element and enclosing the drums and forming therewith the front 85 wall of the firebox, and steam delivery 90 means leading from the upper drums.
8. A locomotive having a fire-box, a barrel, upper drums extending longitudinally of the fire-box and barrel, a water tube generator within the fire-box including a water containing bottom frame element and the upper drums, a plurality of drums within the barrel forming with said upper drums a generator in the barrel, said drums being in communication with said frame element 95 and having their rear ends terminating above a portion thereof, fire tubes in the latter-named drums, and a brickwork filling resting on said frame element and built about the drums and forming a division 100 wall between the fire-box and barrel.
9. In a locomotive, a fire-box, drums at the top of the fire-box, a header at the forward portion of the bottom of the fire-box, water tubes connecting said drums and header, a barrel into which the aforesaid drums extend, other drums arranged within the barrel and having their rear ends overhanging the said header, and brickwork resting on the header and enclosing the 110 overlying portions of the drums and forming therewith the front wall of the fire-box.
10. A locomotive having a fire-box, a barrel, drums arranged within the top of the fire-box at each side of the longitudinal 115 center thereof and extending into the barrel, communicating front, rear and side headers at the bottom of the fire-box, water tubes in the fire-box connecting said drums and headers, bottom drums within the barrel on opposite sides of the longitudinal center thereof, central and side intermediate drums in the barrel, and flow connections in the barrel between each top and bottom 120 drum and the central intermediate drum.
- 130

and between each top and bottom drum and the outer intermediate drum at the same side of the center of the barrel.

11. A locomotive having a fire-box, a barrel, drums arranged within the top of the fire-box at each side of the longitudinal center thereof and extending into the barrel, communicating front, rear and side headers at the bottom of the fire-box, water tubes in the fire-box connecting said drums and headers, bottom drums within the barrel on opposite sides of the longitudinal center thereof, central and side intermediate drums in the barrel, flow connections in the barrel between each top and bottom drum and the central intermediate drum and between each top and bottom drum and the outer intermediate drum at the same side of the center of the barrel, fire tubes in the second-named drums, and brickwork resting on the front header at the bottom of the fire-box and enclosing the overlying portions of the drums and forming therewith the front wall of the fire-box.

25 In testimony whereof we affix our signatures.

GEORGE H. EMERSON.
